Attns.

UNITED STATES PATENT OFFICE

CAROLINE CASPER, OF BOSTON, MASSACHUSETTS

BACK HAIR CONFINER

Application filed April 29, 1933. Serial No. 668,556.

The object of this invention is to provide a simple confiner for use with hair which has been bobbed, and afterward allowed to grow, so that a fringe of back hair, usually curled or waved, depends at the back of the neck, the function of the confiner being to vary the width of said fringe and maintain it at any desired width, and somewhat compactly against the back of the head and neck.

10 Of the accompanying drawing forming a part of this specification,

Figure 1 shows the elements of my improved confiner as conditioned for application to a fringe of back hair.

15 Figure 2 shows the confiner partly engaged with a fringe.

Figure 3 shows the confiner completely engaged with the fringe.

20 Figure 4 shows in perspective the take-up device shown by Figure 1.

Figure 5 shows the take-up device in section, and engaged with the looped cord shown by Figure 1.

The same reference characters indicate the 25 same parts in all of the figures.

12 designates a fringe or layer of back hair depending from the back of the wearer's head and neck.

The confiner comprises two resilient wire 30 hair pins each including two legs 13 connected by a neck 14 at one end of the pin, the legs being normally close to each other, as indicated by Figure 1, and adapted to be sprung apart by hair interposed between 35 them, as indicated by Figure 2.

One leg of each pin includes a bent portion forming a recess 15 having a closed end 16 adjacent to and facing the neck 14.

The pins are insertable in alignment with 40 each other in opposite edges of the fringe 12, with their necks 14 in compressing contact with hair constituting edge portions of the fringe.

The confiner comprises also connecting 45 means adapted to confine the inserted pins with their necks 14 variably spaced apart to determine and maintain any desired width of the fringe 12.

Said connecting means includes a substantially straight flexible cord 17 having at one

end an eye 18 separably engageable with the closed end 16 of one pin recess, and a looped cord having an eye 20 separably engageable with the closed end 16 of the other pin recess, said cord including a main stretch 19, and an 55 end stretch 21, said stretches forming a bight with which the eye 20 is engaged.

The connecting means also includes a take-up device associated with the looped cord and maintaining different operative lengths 60 thereof, said device being in this instance embodied in a metal sleeve including a tubular end portion 24 and a flat sided end portion 22 having an orifice 23. The stretches 19 and 21 of the looped cord extend through, 65 and closely fit, the bore of the end portion 22 and the orifice 23. The operative length of the looped cord may be varied by pulling the end stretch 21 endwise in the sleeve, the close fit of the stretches in the sleeve preventing 70 accidental endwise movement of either stretch.

The cords have complemental coupling 75 members forming their meeting ends. In this instance, one of said coupling members is a metal member 25 fixed to the cord 17, and having a screw-threaded terminal 26. The other coupling member is composed of a metal member 27 having a threaded socket 29 receiving the terminal 26, and a swiveled eye 30 connected with the cord stretch 19, the member 27 being rotatable independently to engage it with, and separate it from, the member 25.

The confiner is applied by first inserting 80 the pins in the fringe without connecting the coupling members, as shown by Figure 2; and then interengaging the coupling members as shown by Figure 3. Before the coupling 85 members are connected the looped cord is lengthened, and after the connection of the coupling members the looped cord is shortened to decrease the distance between the pin necks 14 and thus cause any desired decrease of the width of the depending fringe.

The free outer ends of the fringe hairs 90 may be tucked into the space between the pins and the connected cords so that all portions of the confiner excepting the pin necks 14 are concealed, as indicated by Figure 3.

The free end of the cord stretch 21 is preferably provided with an eye 32 loosely embracing and slideable on the stretch 19 to prevent said free end from swinging outward from the stretch 19.

5 I claim:

A back hair confiner comprising in combination two hair pins, each including two legs connected by a neck at one end of the 10 pin, one leg of each pin including a bent portion forming a recess having a closed end adjacent to and facing the neck of the pin, said pins being insertable in alignment with each other in a fringe of back hair with the necks 15 in compressing contact with hair constituting opposite edge portions of said fringe, and con-

necting means adapted to confine the pins with their necks variably spaced apart to determine and maintain a desired width of the fringe, said means including a substantially straight flexible cord having an eye 70 separably engageable with the closed end of one pin recess, a looped cord having an eye separably engageable with the closed end of the other pin recess, and a take-up device 75 associated with the looped cord, and adapted to maintain different lengths thereof, said cords having complementary coupling members forming meeting ends of the cords and separably interengageable to connect the cords end to end. 80
